UNITED STATES PATENT OFFICE

WILLIAM F. RIEGER, OF SALT LAKE CITY, UTAH, ASSIGNOR, BY MESNE ASSIGNMENTS,
TO THE STOKER MATIC CORPORATION, OF SALT LAKE CITY, UTAH, A CORPORATION
OF UTAH

RETORT

Application filed August 13, 1928. Serial No. 299,176.

My invention relates to retorts for stoker furnaces and has for its object to provide a new and efficient device which will not burn out under excessive heat and one which will give greater combustion to the fuel.

A further object is to provide a light weight, compact retort which will be economical to manufacture, light to handle and easily installed.

10 These objects I accomplish with the device illustrated in the accompanying drawings in which similar numerals and letters of reference indicate like parts throughout the several views and as described in the

15 specification forming a part of this application and pointed out in the appended claims.

In the drawings in which I have shown the best and most preferred manner of building my invention Figure 1 is a plan view of the 20 retort with the outline of the brick furnace wall shown in dotted lines. Figure 2 is a vertical longitudinal section of the device. Figure 3 is an enlarged sectional view showing an air passage and the water chamber more clearly. Figure 4 is a section on line 4—4 of Figure 1. Figure 5 is a horizontal sectional view through an air passage, showing more clearly the arrangement of the deflector plate mounted therein.

30 In the drawings I have shown dotted lines A to indicate the furnace, and with the pipes B and C to indicate the coal inlet and the air inlet pipes respectively. The retort is made by forming square side pieces 1 and 2 and

35 end pieces 3 and 4 together, with the corners rounded forming a retort having the sides longer than the ends and in the form of a rectangle. When welded together the corners are provided with extending lugs 5

40 through which bolts 6 are passed to secure the water chamber D to an air chamber E. The said air chamber E is made by securing side walls of sheet metal together into a box shape having the bottom and top open, and

45 with lugs 8 formed on the corners through which the bolts 6 are passed to hold the water chamber D to the air chamber E. The lower side of the said air chamber is not closed but is set into concrete or brick when the retort is set in a furnace so that no air can escape

through the retort. The top side of the firebox is open and is closed around the edges by the water jacket and the central portion is closed by the curved semicircular sheet of metal 9 which is secured around its edges to the inner lower side of the water jacket and is attached to the coal supply pipe B. The coal supply pipe B is provided with a screw 10 which is rotated to drive the coal into the retort, by screw action and the sloping 55 surface of the plate 9 introduces the coal upwardly around the inner face of the retort. An air inlet pipe C is secured on the front face of the said air chamber E through which air is forced to fill the chamber. Tuyère openings 12 are provided in the front face 14 of semicylindrical pipes 11 which pipes are made in the water chamber D with the flat diameter 13 in alignment with the inner side of the water chamber so that air passing up through 60 the pipes will be forced inwardly through the tuyère openings 12. The bottom ends of the said pipes are welded to the bottom of the water chamber and the opening of the pipe is in open connection with the air chamber 65 E so that when air is forced in at the said chamber it will be forced out into the retort through the tuyère openings 12 by pressure 70 in the said pipes and air chamber. As shown in Figure 3, the tuyère openings may be made 75 at different angles to the front face 14 so that the air introduced therethrough will be directed into the retort in the correct angle and air passing through the upper tuyère openings will be forced inwardly and downwardly 80 while air passing through the lower openings will be forced inwardly and upwardly. The said pipes 11 are provided with deflecting plates 15 which are formed therein to direct 85 the air toward the tuyère openings as necessary. An inlet pipe 16 and an outlet pipe 17 are provided in the water chamber and they are connected with the water jacket of the furnace to provide free circulation of water 90 through the water chamber at all times. 95

The operation of my invention is as follows:

When the coal is introduced onto the pipe B by the screw 10 it is forced inwardly and upwardly against the sides of the water chamber and air is at the same time being forced 100

through the air chamber E and the tuyère openings 12 into the retort and when the coal is ignited by any suitable means the force of air passing through the tuyère openings will create combustion thereof to such an extent that there will be no smoke from the fire. As new coal is introduced the old burning coal and ashes are forced inwardly and upwardly giving way for the new combustion fuel and the process is continued as desired. The air being so introduced creates such a complete combustion that there is no loss of fuel by incomplete combustion and the direction of the tuyère openings introduces the incoming air into the necessary streams for such complete combustion.

Having thus described my invention I desire to secure by Letters Patent and claim:—

1. In a furnace construction, a retort, means for feeding fuel to said retort, and a water jacket surrounding said retort, the walls of said water jacket and the retort defining air passages, each of said passages having a plurality of openings into the retort so as to feed air to a substantial body of the fuel therein.

2. In a furnace construction, the combination of a retort, means for feeding fuel to said retort, an air chamber at the base of said retort, and a water jacket surrounding the retort at the top of said air chamber, the walls of said retort and water jacket defining a plurality of vertically arranged air passages communicating at one end with the air chamber, the wall of the retort being provided with a plurality of openings communicating with each of said air passages and the water of said water jacket being adapted to contact with the walls of the air passages and the wall of the retort intermediate the same so as to cool a substantial area of both said air passages and retort.

3. In an underfed furnace, the combination with a retort having upwardly extending walls provided with a plurality of groups of tuyère openings disposed substantially in alignment, an enclosing wall disposed at the rear of each group of tuyère openings to form air supplying passages and opening downwardly, and a water jacket enclosing the wall of said retort and the passages.

4. In a furnace of the type described, the combination of a retort provided with means for forcing fuel through the bottom, a closed air chamber surrounding the retort and provided with a plurality of passages extending upwardly therefrom in contact with the retort wall and communicating therewith, and common cooling means for said retort and passages.

In testimony whereof I have affixed my signature.

WILLIAM F. RIEGER.
